CLAIM

The ornamental design for a bag with tape strip, as shown and described.

DESCRIPTION

FIG. 1 is a top perspective view of a bag with tape strip showing the claimed design in an open configuration.

FIG. 2 is a left side view thereof.

FIG. 3 is a right side view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a top perspective view of the claimed design in a closed configuration.

FIG. 9 is a left side view thereof.

FIG. 10 is a right side view thereof.

FIG. 11 is a front elevation view thereof.

FIG. 12 is a rear elevation view thereof.

FIG. 13 is a top plan view thereof; and,

FIG. 14 is a bottom plan view thereof.

The broken lines shown in the drawings depict portions of the bag with tape strip that form no part of the claimed design.

1 Claim, 9 Drawing Sheets
